UNITED STATES PATENT OFFICE.

FRANK J. M. CURRAN, OF GRAND RAPIDS, MICHIGAN, ASSIGNOR TO GRAND RAPIDS
REFRIGERATOR CO., OF GRAND RAPIDS, MICHIGAN, A CORPORATION OF MICHIGAN.

REFRIGERATOR CONSTRUCTION.

1,274,389.

Specification of Letters Patent.

Patented Aug. 6, 1918.

Application filed January 2, 1918. Serial No. 209,938.

To all whom it may concern:

Be it known that I, FRANK J. M. CURRAN, a citizen of the United States of America, residing at Grand Rapids, in the county of 5 Kent and State of Michigan, have invented certain new and useful Improvements in Refrigerator Constructions; and I do hereby declare the following to be a full, clear, and exact description of the invention, such as 10 will enable others skilled in the art to which it appertains to make and use the same.

This invention relates to improvements in refrigerators, and is particularly concerned with linings for refrigerators, so constructed 15 as to include provision compartments and an ice box, whereby all can be covered on their inner sides with porcelain to provide an especially cleanly and sanitary lining which can with ease and facility be kept in a clean 20 condition. It is a primary object and purpose of the present invention to so form the lining that this can be attained, together with the construction of the lining in a simple and comparatively economical manner. 25 Various other objects and purposes in addition to those enumerated will appear as understanding of the construction is had from the following description, taken in connection with the accompanying drawings, in 30 which,

Figure 1 is a perspective view of the refrigerator lining.

Fig. 2 is a horizontal section taken substantially on the plane of the line 2—2 of 35 Fig. 1.

Fig. 3 is a similar view on the plane of line 3—3 of Fig. 1, and

Fig. 4 is a fragmentary perspective and sectional view, the section being taken on 40 the line 4—4 of Fig. 1.

Like reference characters refer to like parts in the several views of the drawings.

The lining is made of sheet metal and includes a back 1 from the vertical side 45 edges of which, sides 2 and 3 are bent in a forward direction. A top 4 and a bottom 5 are welded to the top and bottom edges of the back and sides of the lining, leaving the front side open.

50 The front edge of the side 2, preferably, is bent inwardly, as indicated at 6, and is then curved reversely at 7 terminating in an outwardly turned lip 8, as shown, this being similar to the construction shown in

United States Patent No. 1,147,288 issued 55
July 20, 1915.

Substantially midway between the sides of the lining a vertical post formed of metal is provided and inserted between the top 4 and bottom 5 thereof being welded at its ends to said top and bottom. The upper part of the post includes a flat section 9 paralleling the back 1, which is then bent forward at right angles for a short distance, as indicated at 10, then again at right angles 65 parallel to the section 9 for a distance, as indicated at 11, and thence bent at right angles to the rear as indicated at 12, the metal being then formed into a substantially U-shaped loop having a leg 13, integral with and extending from the part 12, a bend 14 and a terminal leg or lip 15. This U-shaped loop consisting of parts 13, 14, and 15 is similar in form to the one indicated by parts 6, 7, and 8 at the front edge 70 of the side 2, but is bent and positioned oppositely thereto as shown. It also extends the full height of the refrigerator lining. At a point substantially one-third of the distance above the base 5, though it is to be 80 understood that this point is not at any fixed or definite location, the post is slit at the side opposite the U-shaped bend therein and that part below the slit is formed with a back 16, one edge of which is bent as 85 previously described to include the parts 14, and 15, while the opposite edge is similarly bent in an opposite direction to form a U-shaped bend 17 as best shown in Figs. 1 and 3.

A tray is located within the lining and at its front inner corner rests upon the upper edges of the parts 16 and 17. It is positioned horizontally and is made of sheet metal comprising a bottom 18 and upstanding sides 19. The side 3 and a part of the back 1 are divided or slit, the upper parts of the sides 19, adjacent said side 3 and back, being turned outwardly through the slit, as indicated at 20 in Fig. 4, and thence 95 bent upwardly at 21 along the outer side of the side 3 and the back 1, being permanently secured in place in any suitable manner, preferably, by spot welding. The front edge of the side 3 above the tray is turned 100 inwardly for a distance as indicated at 22, while the front edge of the side 3 below the tray is formed with a substantially U-shaped 105

bend 23, like that shown at 17, but bent in a reverse direction. In addition a bead 24 is pressed inwardly from the back above the rear upper corner of the tray, it having a vertical side 25 positioned in the same plane with the part 12 heretofore described, whereby a partition 26 may be located within the lining above the tray to complete the ice box, the tray forming the lower member or bottom thereof. This partition lies against the sides 25 and 12 and may be secured in place in any suitable manner. It, however, does not in the present instance form any particularly important or essential feature of the invention.

A lining of the construction described may be assembled and the parts welded together, after which the inner portions thereof may be given a porcelain coating which is baked permanently thereon. In this manner the provision compartments below and to one side of the ice box, together with the ice box, are completely covered with a porcelain inner lining which is especially clean and sanitary. The frame-work of the refrigerator may be built around the lining and the doors hung thereon for entrance into either the ice box or the provision compartment. With this construction a minimum amount of metal is used for building the metal lining for the refrigerator, and the entire inner surface thereof may be completely coated with porcelain at one operation and at a minimum of expense.

This is a feature of great importance in refrigerator construction. Moreover, the attachment of the tray 18 in the manner described guards against the entrance of water between the sides of the tray and the side and back of the lining, and at the same time a smooth surface or joint is made between the tray and the back and sides of the lining which may be very easily reached for cleaning.

I claim:

1. A refrigerator construction including an inner metal lining comprising a back, sides, bottom and top, with a post disposed between the top and bottom of the lining at the front edges thereof and at a point between the sides, and a tray secured to one side and a part of the back of the lining and supported at one corner by the post a distance above the bottom of the lining, substantially as described.

2. A refrigerator construction including an inner metal lining comprising a back, sides, bottom and top, with a post disposed between the bottom and top of the lining at the front edges thereof and at a point between the sides of the lining, a tray carried by the post and by one side and a part of the back at a point a distance above the bottom, and a partition disposed above the tray

and located between the post and said back, substantially as described.

3. A refrigerator construction including an inner metal lining comprising a back, sides, bottom and top, with a post disposed between the bottom and top of the lining at the front edges thereof and at a point between the ends of the lining, and a tray located between the post and one side and the back of the lining, said tray having upwardly extending sides which are bent to pass through said side and back of the lining and then extend upwardly along the outer side of said side and back, substantially as described.

4. A refrigerator construction including a lining comprising a back, sides, bottom and top, a post disposed between the top and bottom of the lining at the front edges thereof and at a point between the sides, a tray located between the post and one side and the back of the lining and supported thereby a distance above the bottom of said lining, a rib in the back of the lining above the rear inner corner of the tray, and a vertical partition disposed between the tray and the top of the lining, said partition bearing against the post and said rib at its front and rear edges, respectively.

5. A refrigerator construction including a lining comprising a back, sides, bottom and top, a post disposed between the top and bottom of the lining at the front edges thereof and at a point between the sides, said post being partially divided a distance above its lower end and formed below said point with a back and two oppositely disposed and forwardly turned substantially U-shaped bends at the sides thereof, and a tray resting at its front inner corner upon the upper end of said lower portion of the post and secured at one side and at the back to a side and the back of the lining, substantially as described.

6. A refrigerator construction including a lining comprising a back, sides, bottom and top, a post disposed between the top and bottom of the lining at the front edges thereof and at a point between the sides, said post being partly divided horizontally from one side edge thereof toward the other a distance above its lower end and formed below said division point with a back and two oppositely disposed and forwardly turned substantially U-shaped bends at the sides thereof, one of said bends extending the full length of the post, and above said division point with a forwardly turned section bent from the rear leg of said last mentioned U-shaped bend and which extends a short distance in front of said bend, then turned at right angles for a distance and then to the rear at right angles for a short distance, terminating in a section paralleling the back of the lining, and a tray disposed horizon-

tally within the lining and bearing at its front inner corner on the upper end of said lower portion of the post, and connected at one side and back to a side and the back of the lining.

7. A refrigerator construction containing the elements in combination claimed in claim 6, said side of the lining to which a side of the tray is connected being formed at its

front edge below the tray with an inwardly 10 and forwardly turned U-shaped bend, and above the tray being turned inwardly, and the other side of the lining at its front edge being formed for its full length with an inwardly and forwardly turned U-shaped 15 bend, substantially as described.

In testimony whereof I affix my signature.
FRANK J. M. CURRAN.
